Primary Examiner — David Muller*(74) Attorney, Agent, or Firm* — Jeremy Jay**CLAIM**

The ornamental design for an applicator device, as shown and described.

DESCRIPTION

FIG. 1 is a front elevation view of an applicator device of the present invention.

FIG. 2 is a rear elevation view thereof.

FIG. 3 is a top plan view thereof.

FIG. 4 is a bottom plan view thereof.

FIG. 5 is a right side elevation view thereof.

FIG. 6 is a left side elevation view thereof.

FIG. 7 is a perspective view thereof from above.

FIG. 8 is a perspective view thereof from below.

FIG. 9 is a perspective view thereof from above showing the article with the cap down.

FIG. 10 is a perspective view thereof from below showing the article with the cap down.

FIG. 11 is a sectional view thereof taken along line 11-11 in FIG. 5.

FIG. 12 is a sectional view thereof taken along line 11-11 in FIG. 5 showing the article with the cap down; and,

FIG. 13 is a sectional view thereof taken along line 11-11 in FIG. 5, showing the occasion of use.

The features shown in broken lines depict environmental subject matter only and form no part of the claimed design.

1 Claim, 13 Drawing Sheets
